Primary Examiner — Khawaja Anwar*Assistant Examiner* — Mojtaba Tehrani(74) *Attorney, Agent, or Firm* — Hovey Williams LLP(57) **CLAIM**

The ornamental design for an assault rifle, as shown and described.

DESCRIPTION

FIG. 1 is a left side perspective view of an assault rifle, showing our new design;

FIG. 2 is a right side perspective view thereof;

FIG. 3 is a left side elevation view thereof;

FIG. 4 is a front elevation view thereof;

FIG. 5 is a right side elevation view thereof; and,

FIG. 6 is a top plan view thereof.

The broken lines within the drawings disclose unclaimed portions of the assault rifle and form no part of the claimed design.

1 Claim, 6 Drawing Sheets(56)
